UNITED STATES PATENT OFFICE

104,884

DESIGN FOR A MULTIPLE COMPARTMENT REFRIGERATOR CONTAINER UNIT

Lewis H. Scurlock, Chicago, Ill.

Application October 1, 1936, Serial No. 65,099

Term of patent 14 years

To all whom it may concern:

Be it known that I, Lewis H. Scurlock, a citizen of the United States and resident of Chicago, in the county of Cook and State of Illinois, have invented a new, original, and ornamental Design for a Multiple Compartment Refrigerator Container Unit, of which the following is a specification, reference being had to the accompanying drawing forming a part thereof.

The single figure is a perspective view of a multiple compartment refrigerator container unit, showing my new design.

The essential and characteristic feature of my design resides in the container element illustrated in full lines, comprising a plurality of compartments of the form and arrangement shown.

I claim:

The ornamental design for a multiple compartment refrigerator container unit, as shown and described.

LEWIS H. SCURLOCK.
